AVIATION GASOLINE

Robert E. Barnum, Roselle, N.J., assignor to Esso Research and Engineering Company, a corporation of Delaware

No Drawing. Application February 20, 1956
Serial No. 565,383

2 Claims. (Cl. 44—56)

The present invention is concerned with an improved aviation gasoline. In accordance with the present invention the improved aviation gasoline is secured by using critical amounts of aromatic hydrocarbons in conjunction with diisopropyl ether. The preferred aviation gasolines of the present invention comprise petroleum hydrocarbon mixtures containing critical concentrations of aromatics, particularly aromatics containing between 7 and 9 carbon atoms in the molecule in conjunction with critical proportions of diisopropyl ether. This application is a continuation-in-part of Serial No. 263,021, filed December 21, 1951, and now abandoned.

It is well known in the art to prepare aviation fuels by various methods and processes and to use with these aviation motor fuels blending agents, such as branched-alkyl-ethers, amines and the like. The aviation gasolines of necessity have a designed boiling range from about 100° F. to 350° F. These aviation gasolines also, in order to be entirely satisfactory, must meet certain specifications with respect to the minimum octane number secured with a lean mixture and with a rich mixture. In addition, the fuels must meet other requirements, as for example, a minimum B.t.u. value available per pound, an acceptable tolerance of water contact without excessive loss by solution in the water, a low freezing point and a low or negligible content of non-volatile gum or residue upon evaporation.

The use of branched-ethers for decreasing the knocking tendency of gasoline motor fuel was first disclosed in U.S. Patent 2,046,243. Among the branched ethers disclosed for that use are methyl-tertiary-butyl ether, methyl-tertiary-amyl ether, di-tertiary-butyl ether and other homologs having a total of from 4 to 8 carbon atoms in the molecule and having at least one branched-alkyl group. Diisopropyl ether, or isopropyl ether as it is commonly called, is typical of the branched ethers of the prior art, which taught its use for blending with a motor fuel in concentrations of 5% to 50% or more. The use of methyl-tertiary butyl ether for blending in aviation gasoline to attain particularly desirable antiknock levels was again taught in U.S. Patent 2,409,746. However, the calorific value of methyl-tertiary butyl ether is considerably less than that of diisopropyl ether. Hence its use in an aviation gasoline is much less desirable.

The branched ethers have high antiknock value in aviation gasoline in both lean and rich fuel-air mixtures. However, the ethers have lower calorific value than the hydrocarbons of which aviation gasoline consists and, since the range of flight of aircraft depends upon the calorific value of the load of fuel the aircraft can carry, it has not been practical to use the ethers in substantial proportions in such fuel. It is a well-established principle in the art that such fuel shall have at least 18,700 B.t.u. per pound as its net calorific value. An aviation gasoline, of grade 100/130 as defined in the U.S. Specification MIL-F-5572, was tested and found to have 19,000 B.t.u. per pound, net heating value. A blend of 5% diisopropyl ether in that fuel had 18,880 B.t.u. per pound, net heating

2

value. It is therefore to be understood that in accordance with the present invention diisopropyl ether is blended in concentrations between 3% and 7% by volume in aviation gasoline. Adding less than 3% ether provides no measurable increase in octane rating of the gasoline, while 3% ether increases the octane rating of a 100 O.N. aviation gasoline to 100.2. This octane increment is close to the limit of accuracy of the determination. On the other hand, adding more than about 7% of ether to the aviation gasoline, not only results in a composition having a calorific value of less than the required 18,700 B.t.u., but also results in a lowered rate of increase of octane number; the octane blending value of the ether drops off at above 7% in an aviation gasoline.

Among the types of hydrocarbons, for example, paraffins, isoparaffins, naphthenes and aromatics, which may be present in aviation gasoline, the aromatic hydrocarbons have the lowest heating value per pound. It has therefore been accepted practice in the manufacture of aviation gasoline to limit its volumetric content of aromatic components, all of which have less than 18,000 net B.t.u. per pound, to a maximum total concentration of 25% and usually to a concentration not exceeding 20% in a wholly hydrocarbon composition. Since the motor octane number of most of the aromatic hydrocarbons in the boiling range of aviation gasoline is as high as, or higher than, the octane number of most of the branched ethers and of diisopropyl ether in particular; and since the heating value of the ethers is lower than the heating value of the aromatics, it has not hitherto been practical to use, as blending agents together in aviation gasoline, both the branched ether and the aromatic hydrocarbon type of components. As will be pointed out below a distinction must be observed between specification aviation gasoline suitable for use in multi-cylinder aircraft engines, and experimental aviation fuels tested for antiknock value in single cylinder supercharged engines. In accordance with the present invention, aromatic hydrocarbons of 7 to 9 carbon atoms per molecule, and preferably those of 8 or 9 carbon atoms, are blended in aviation gasoline in a maximum total concentration of 15% of aromatics along with the diisopropyl ethers. Benzene cannot be used because its freezing point is too high.

As has previously been noted, some branched ethers have high antiknock value in aviation gasoline. Their blends have good water tolerance in terms of negligible loss by transfer of blending agent from the gasoline phase to the water phase. However, the blends can and do dissolve more water, at any given temperature, than does aviation gasoline of wholly hydrocarbon composition. In the processes of manufacture and of storage, aviation gasoline may become saturated with water, with which it may come into contact. Such a condition may be where aviation gas is stored over water as in aircraft carriers. A typical aviation gasoline saturated at about 70° F. temperature contains about 0.003% water by volume. Blends of as little as 5% of branched ether in such an aviation gasoline contain at saturation at least 0.006 and up to 0.01% of water by volume.

The solubility of water in aviation gasoline and in blends of branched ethers with aviation gasoline decreases markedly with decreasing temperature. The solubility of water is decreased about ten-fold when the temperature is decreased from 100° F. to 0° F. A drop of temperature of 100 degrees or more is normally encountered in the fuel systems of aircraft between ground level and high altitude in flight. When the temperature drops, the water, which was in solution at the higher temperature, is precipitated at the lower temperature. When the lower temperature is below 32° F., the water is pre-

cipitated as a solid, in the form of crystals of ice or of snow.

This phenomenon is particularly observed in the case of diisopropyl ether. The latter is a particularly desirable constituent of aviation gasoline as pointed out but hitherto this material, though in large supply from refinery operations, has not been able to be utilized for this purpose because of the icing problem. On the other hand, more costly ethers, such as ethyl tertiary butyl ether, do not exhibit this icing tendency. Therefore, the invention has for its main purpose the utilization of diisopropyl ether in aviation gasolines in the presence of water. Ethyl tertiary butyl ether in 5% concentration forms no ice when present in aviation gasoline saturated with water at no temperature as low as -76°F .

The fuel systems of aircraft are provided with fine filters of 80 mesh per inch, for example, or even with pores of only 10 microns diameter; which are quickly plunger by ice crystals, with disastrous results for the aircraft when the flow of fuel is thus suddenly interrupted. The greater the initial content of water in the fuel, the greater is the weight of ice precipitated from a given volume of fuel or within a given time of fuel flow through the filter. From blends of branched ethers in aviation gasoline, not only is the amount of solidified water thus precipitated greater than for ordinary aviation gasoline, but also the water normally solidifies in the form of flaky snow with greater tendency for plugging filters than fine ice crystals would have.

Table I demonstrates that it is possible to add 5% of diisopropyl ether to commercial aviation gasoline of 100/130 grade and meet all requirements of the Defense Department specification for aviation gasoline MIL-F-5572. It should be further noted that when dry ether is employed for this purpose a gasoline passing the freezing point requirements is obtained. As will be shown below this is not true when diisopropyl ether in 5% amounts is employed in conjunction with aviation gasoline that is saturated with water.

TABLE I

Quality aspects of using diisopropyl ether

	No Ether	5% Diisopropyl Ether (Dry)	Aviation Gasoline Specification MIL-F-5572

100 Octane No. in lean mixture (12 to 14 lbs. air per lb. of fuel).
130 Performance No. in rich mixture (9 to 10 lbs. air per lb. of fuel).

Among the types of hydrocarbons which may be present in aviation gasoline in substantial proportions, the aromatics have the greatest tendency to dissolve water. At 100°F , for example, benzene and toluene dissolve about 0.45 mol percent water, whereas the naphthenes and isoparaffins in aviation gasoline dissolve about 0.13

mol percent water. At 50°F , the comparable solubilities of water are, respectively, 0.17 mol percent and 0.035 mol percent. Since a high degree of solubility of water in aviation gasoline at ordinary temperatures is normally undesirable for the reasons previously stated and since both the branched ether and the aromatic hydrocarbon type of components tend to dissolve more water than does ordinary aviation gasoline, it has not hitherto been practical, for these additional reasons to use both those types of components together in blends of aviation gasoline saturated with water.

It has now been found that if aromatics are used in conjunction with diisopropyl ethers in controlled amounts in water saturated aviation gasoline, all the specifications and all the quality requirements may be met and the tendency to ice is corrected.

The present invention may be more readily understood by the following examples.

20

EXAMPLE 1

The particular value of C_8 and C_9 aromatics for this effect upon the icing tendency of water-saturated gasoline is contrasted with the effect of C_{10} and C_{12} aromatics in the following table, showing the results for $\frac{1}{2}$ hour cooling of gasoline to -50°F , of water-saturated gasoline at 75 cc./min./sq. inch flow rate through 10 micron filter.

Component	Vol. Percent	Motor Octane No. Unleaded
Diisopropyl Ether	5.0	98.9
C ₄ Aviation Alkylate	45.6	92.0
Virgin Base Naphtha	25.8	74.0
Aromatics ¹	10.8	100.0
Isopentane	12.8	90.3

¹ 50% xylene and 50% toluene.

The aromatics content of the virgin naphtha is about 5%, and the total concentration of aromatics in the aviation gasoline is about 12.1%. It is to be noted that all the constituents, save the aromatics have lower Motor Octane Numbers than the diisopropyl ether.

The gasoline contained 4.6 cc. of tetraethyl lead in the form of 1-T ethyl fluid per gallon. The inhibitor used was 1.0 pound of 2,6-di-tertiary butyl-para-cresol per 5000 gallons. Red dye was added to the gasoline in a concentration of 0.28 gram per 100 gallons. The gasoline as constituted above had a grade rating of 108/145.

EXAMPLE 3

Diisopropyl ether, particularly in concentration of about 5%, has lean antiknock performance superior to that of alkylate and rich performance equal to that of toluene. This ether is therefore particularly advantageous for obtaining any desirable balance between the lean and rich antiknock performance of aviation gasoline blends. A comparison of the antiknock blending characteristics of the three blending agents in aviation gasoline of grade 100/130, all the blends having 4.6 cc. of tetraethyl-lead per gallon, is as follows:

	At Lean Mixture-Blending Octane No.	At Rich Mixture-Blending Index No.
Grade 100/130	100	130
Diisopropyl Ether	129	248
Butenes Alkylate	107	150
Toluene	101	250

EXAMPLE 4

The low temperature filterability of water-saturated aviation gasoline containing 5% diisopropyl ether and varying concentrations of aromatics was compared with that of a gasoline containing no ether. The gasolines were saturated with water at room temperature, chilled down to -20° F. within 1/2 hour and filtered through a standard aircraft filter medium having pores of 10 micron diameter. The rate of fuel flow was comparable with the actual rate of flow in aircraft fuel systems. The rate was 100 cc. per minute for each square inch of filter surface.

Composition of gasoline, vol. percent:				
Aromatics (mixed C ₇ and C ₈)	0	5	15	25
Alkylate and Virgin base (2/1 ratio)	95	90	80	75
Diisopropyl Ether	5	5	5	0
	100	100	100	100
Vol. percent water at room temp. saturation	0.006	0.007	0.008	0.005
Mins. elapsed before filter plugs at -20° F.	20	No plug	No plug	No plug

"No plug" indicates that all the gasoline sample was pumped through the filter during an elapsed time of 1 1/2 to 2 hours without interruption by filter plugging at -20° F.

EXAMPLE 5

As a further demonstration of the beneficial effects obtainable by the composition of the invention, low temperature filterability tests with diisopropyl ether blends

were carried out as a series of temperature levels, with the results shown below:

Low temperature filterability of diisopropyl ether blends

[Filtration through 10 micron filter (0.4 sq. in. area) located 1/2" off tank bottom. Fuel mildly agitated during cooling and filtering.]

	Percent Diisopropyl Ether	Percent Avia. Toluene	Percent Alkylate+Virgin Base
Blend A	5	0	95
Blend B	5	15	90

[Effect of filtration temperature on plugging time 100 cc. min./sq.in., 1/2 hour cooling rate.]

Temperature	0° F.	-20° F.	-50° F.
Blend A	Plugged @ 15 Mins.		
Blend B	No Plug (105 Mins.).	No Plug (106 Mins.).	No Plug (120 Mins.).

EXAMPLE 6

To show the adverse effects upon the low temperature characteristics of water-saturated aviation fuel compositions when diisopropyl ether is employed with more than the critical amount of aromatics, the following data are presented. Blends of isoctane, diisopropyl ether and aromatics C₈ and/or C₇ were shaken vigorously with water and stored over water for 24 hours. Thereafter the "freezing" point was determined. The latter is defined as the temperature at which the formation of a solid phase or crystals first become visible in a test tube. Since the specifications for aviation gasoline require a maximum freezing point of -76° F., it is customary to report only "below -76° F." when a sample passes specification.

Diisopropyl ether, Vol. Percent	Isooctane, percent	Aromatics, Percent	Crystals, ° F.
40	91.0	6.0	<-76
3	84.2	10.8	<-76
5	84.0	9.0	<-76
7	76.0	19.0	-15
5	48.5	48.5	-44
3	47.5	47.5	-40
5	46.5	46.5	-28
7			

The above data also demonstrate clearly that when only slightly more than the critical amount of aromatics is employed together with the diisopropyl ether, the freezing point of the water-saturated blends rises precipitously. These are blends of pure hydrocarbons, not adjusted to proper volatility for use as commercial aviation gasoline.

EXAMPLE 7

Though methyl tertiary butyl ether, because of its lower calorific content, is not a desirable constituent for aviation gasoline, it behaves like diisopropyl ether in low temperature characteristics in water saturated fuel blends when associated with low and high concentrations of C₈ aromatics. This is readily apparent in the data below:

Methyl tert. Butyl Ether, Vol. Percent	Isooctane, Percent	Aromatics, Percent	Crystals, ° F.
65	90.2	4.8	<-76
5	47.5	47.5	-38
5	46.5	46.5	-25
7	33.4	33.3	+10
33.3	25.0	25.0	+15
50.0			

What is claimed is:

- An improved aviation gasoline adapted for filterability at temperatures below the freezing point of water present therein and having a net calorific value of at least 18,700 B.t.u. per pound and having an initial boil-

ing point of about 100° F. and a final boiling point of about 350° F. comprising essentially petroleum hydrocarbon constituents containing between about 3% and 7% by volume of diisopropyl ether and 3% to 15% of aromatic hydrocarbons having from 7 to 9 carbon atoms, the ratio of said ether to said aromatic hydrocarbon being greater than 5/19, said gasoline being further characterized in containing at least 0.006% by volume of liquid water.

2. The composition of claim 1 containing from 0.006 to 0.01% water.
